Charles Whitney

UNITED STATES PATENT OFFICE.

CHARLES WHITNEY, OF CHICAGO, ILLINOIS.

PHOTOGRAPHIC-PLATE HOLDER.

SPECIFICATION forming part of Letters Patent No. 446,371, dated February 10, 1891.

Application filed February 3, 1890. Serial No. 339,046. (No model.) Patented in Italy April 29, 1890, No. 27,256/333; in Canada July 2, 1890, No. 34,607, and in France July 17, 1890, No. 204,797.

To all whom it may concern:

Be it known that I, CHARLES WHITNEY, a citizen of the United States, residing at Chicago, in the county of Cook and State of Illinois, have invented new and useful Improvements in Photographic-Plate Holders for Cameras, (patented to me in France, No. 204,797, dated July 17, 1890, in Italy, No. 27,256/333, dated April 29, 1890, and in Canada, No. 34,607, dated July 2, 1890,) of which the following is a specification.

My invention relates to improvements in photographic cameras in which one or more friction feed-rollers are used; and the objects 15 of my improvements are to provide a receptacle or magazine for a series of plates cut to any desired size and means for feeding them to the proper position for exposure, and in providing a receptacle and means for placing 20 the plates therein after the exposure is made, and also means for determining the proper position of them for exposure. I attain these objects by the mechanism illustrated in the accompanying drawings, in which—

25 Figure 1 is a front view. Fig. 2 is an end view. Figs. 3 and 4 are cross-sectional views.

Similar letters refer to similar parts throughout the several views, in which—

A is the main frame, and B the slide; C, 30 the thumb-wheel; D, the lifting-bar attached to the slide.

I' are the negative-plates.

M' is a frame supporting the unexposed plates pivoted and held in position at X'.

35 R is a glass support, and J is a wedge-shaped block, between which and the glass R the negative-plate is held in position.

S is a spring which holds the plates against the feed-roller.

40 U U are index-points on chain V.

W are chain-pulleys attached to the shaft of the feed-rollers.

I' I' are the feed-rollers for moving the plates.

45 In operation my invention is an attachment for cameras, and may be made of any size required for the various-sized cameras and attached or connected in the usual manner for plate-holders or roll-holders. By removing 50 the back board of main frame A the plate-

receptacle M' is swung out and filled with flexible plates properly sensitized. The back board is then replaced, and the pressure of the springs S holds the upper end of the negative, against the feed-roller. By turning the 55 thumb-wheel C until the chain V has made one-half revolution a plate is brought into position for exposure, the engagement of the upper feed-roller having forced the plate between the glass R and block J. In this position the slide B is withdrawn and the exposure is made. By revolving the feed-rollers in the direction indicated by the arrow in Fig. 2 another plate is brought into position for exposure, and the previously-exposed plate is 60 forced into space N' by engaging with the lower feed-roller. The feed-rollers I' are held in unison by the chain V, and the position of the plate is determined by the index-points on the chain.

I do not claim as my invention the broad feature of a rotary transferring device which impinges upon the surface of the sensitive plate or its holder for the purpose of transferring it from one compartment to another; but,

Having thus described my invention, what I claim is—

1. In a plate-holder for cameras, the combination of the magazine of plates, the block J, the feed-rollers I', and the glass-support R, 80 substantially as described.

2. In a plate-holder attachment for cameras, the chain X, with index-points U U and pulleys W W, arranged for keeping the feed-rollers in unison and designating the distance 85 of length of travel for each plate, substantially as described.

3. In a plate-holder for cameras, the combination of the feed-rollers I', the pulleys W, and the chain V, substantially as described. 90

4. In a photographic-plate holder for cameras, the friction-rollers I' I', one adapted to force the plate into position for exposure and the other adapted to force it into the space N, in combination with the chain V and the pulleys W, substantially as described. 95

CHARLES WHITNEY.
